EGG CARTON

Paul K. Schilling, Waterville, Maine, assignor, by
mesne assignments, to General Package Cor-
poration, a corporation of Delaware

Application October 30, 1947, Serial No. 783,021

6 Claims. (Cl. 229—44)

1

My invention relates to an improvement in egg cartons wherein it is desired to provide a means of packing egg cartons in a minimum of space.

Eggs are most commonly shipped in egg cartons which often contain thirty dozen eggs. These cartons are most commonly formed with two egg receiving compartments, each of which is designed to contain five layers of three dozen eggs. The eggs are usually separated by means of partition forming fillers, while flats of suitable design are interposed between the various layers. The eggs thus packaged are usually placed in suitable containers by the merchants receiving the eggs and are sold in these cartons. This arrangement necessitates handling of the eggs by the merchant, thus requiring time and labor.

More recently it has been proposed that the egg producer package the eggs directly in cartons which may be shipped to the merchant in condition for immediate sale. However, in order to properly protect the eggs during shipment the cartons ordinarily employed have required more space than is usually required in egg cases of conventional size. As a result special larger cases were required, resulting in additional costs and lost space in shipment. The egg cases of sufficiently large size to contain the individual cartons of eggs were sufficiently larger to result in a considerable added expense in carload shipments.

It is the object of the present invention to produce a carton capable of holding a dozen eggs or the like and in so designing the cartons that they do not require more space than the conventional layers of eggs in an egg case. As a result the egg cases in common use at the present time may be used to contain thirty dozen eggs packaged in individual cartons, each holding a dozen eggs.

A feature of the present invention lies in the provision of cartons capable of protecting the eggs in shipment and having a flange extending thereabout. This flange is higher on one side of the package than it is on the other side thereof so that the flange on one package may overlap the flap of the next adjacent package. As a result the distance between adjacent packages is divided in half so that the cartons may be packed in conventional egg cases.

A feature of the present invention lies in the provision of an egg carton having top and bottom portions which are provided with a peripheral flange extending thereabout. This peripheral flange is of substantial thickness so as to

2

protect the contained eggs. The flange on one side of each carton is lower than the flange on the other side of the carton. As a result adjacent cartons may be rested upon a flat plane with the flanges of adjacent cartons in overlapping relation.

A feature of the preferred form of my carton lies in the fact that ventilating space may be provided when desired between certain of the carton layers. As a result the body of the carton need not be weakened by ventilating openings when ventilation is desired.

An added feature of the present invention resides in providing egg cartons having a flange extending thereabout and in providing a means of overlapping the flanges of adjacent cartons while the bases of the cartons remain on a flat plane. By this construction adjacent cartons are held in spaced relation by the combined action of two flanges, each of which is connected to one of the cartons and extends into contacting relation with the wall of the other cartons. Thus the cartons are more efficiently held in placed relationship than would be the case if the flanges extended into abutting relationship.

These and other objects and novel features of my invention will be more clearly and fully set forth in the following specification and claims.

In the drawings forming a part of my specification:

Figure 1 is a top plan view of my carton in open position showing the construction thereof.

Figure 2 is an end elevation view of the carton in open position.

Figure 3 is an end elevation view of the carton in closed position.

Figure 4 is an end elevation view of a plurality of similar cartons arranged in adjacent relationship.

Figure 5 is an end elevational view of a modified form of carton, the view showing several cartons in adjacent relationship.

Figure 6 is a view similar to Figure 5 showing another modified form of carton flange construction.

The carton A illustrated in Figures 1 through 4 of the drawings preferably comprises three individual sections hingedly connected together. The intermediate section 10 forms a compartmented tray for receiving a dozen eggs. A complementary egg enclosing section 11 is hingedly connected to the section 10 along a longitudinal edge 12. A cover section 13 is hingedly connected to the opposite longitudinal edge of the section 10 along a hinge line 14. The eggs are

preferably placed in the section 10, the section 11 is folded to overlie the section 10, and the section 13 is folded to overlie the section 11 as illustrated in Figures 3 and 4 of the drawings.

The sections 10 and 11 are shown in the drawings as being of similar form, although they need not necessarily be identical in size or shape. The section 10 includes a series of egg receiving pockets 15 of suitable size and shape. The pockets 15 are spaced by inwardly extending integral projections 16 on the marginal edges of the section and by separating posts 17 between adjacent rows of pockets. The specific shape and construction of the pockets 15 and of the section 10 is not of utmost importance except that the section is tray shaped in general, with downwardly sloping longitudinal side walls 18 and similarly sloping end walls 19 which are provided with integral projections 16 to divide the section into egg receiving recesses capable of holding eggs in spaced relation. The posts 17 are integral with the base of the tray and are connected together by partition walls 20. Similar partition walls 21 connect the various posts 17 to adjacent projections 16 to help form a division between the various pockets. The tray-like section is provided with an encircling flange 22 which includes end flange portions 23 and longitudinal flange portions 24 and 25. The hinge line 14 extends along the flange portion 24, while the hinge line 12 extends along the flange portion 25.

The top enclosing section 11 is shown similar to the section 10. The section 11 includes egg receiving pockets 26 which are complementary to the pockets 15 and are directly opposed to the pockets 15 when the carton is closed. The pockets 26 are formed by inwardly extending projections 27 on the side walls 29 and end walls 30. Posts 31 are provided between the rows of pockets 26, these posts 31 abutting the posts 17 of the section 10 in closed position of the carton. Partition walls 32 connect the various posts and similar partition walls 33 connect the posts 31 to the adjacent projections 27. The eggs in the various pockets are held from lateral movement by the posts, projections and connecting partition walls.

The side and end walls 29 and 30 slope inwardly and a marginal flange encircles the periphery of these walls. The marginal flange 34 includes longitudinal flange portions 35 and 36 and end flange portions 37.

The top or cover section 13 comprises a tray shaped body having sloping longitudinal walls 39 and similarly sloping end walls 40. A top cover panel 41 is supported by the walls 39 and 40 to form a top closure for the carton on which suitable indicia may be printed if desired. A flange 42 peripherally encircles the walls 39 and 40. The flange 42 includes longitudinal flange portions 43 and 44 and end flange portions 45.

As best illustrated in Figure 2 of the drawings the end flange portions 23 of the middle section flange 22 are off-set intermediate the longitudinal edges of the section at a point 46 spaced from the longitudinal center of the section. As a result the flange portion 24 is at a lower level than the longitudinal flange portion 25 and the portion of the end flanges 23 on one side of the off-set 46 are on a lower level than the end flange portions on the other side of the off-set 46. Thus the flange 22 is higher on one longitudinal edge than along the opposite longitudinal edge for a purpose which will be later described in detail.

The end flange portions 37 of the flange 34 are also arranged on two different levels connected by an off-set 47. The portion of the end flanges on one side of the off-set 47 are lower than the end flange portions on the other side of the off-set. Thus the top of this section is arranged on two spaced planes so that the longitudinal flange 35 is lower than the longitudinal flange 36.

It will be noted from Figure 2 of the drawings that the longitudinal flange 25 of the section 10 is on a higher level than the adjacent longitudinal flange portion 35 of section 11 so that the connecting hinge 12 is vertically off-set as illustrated.

The flange 42 of the cover section 13 is arranged on two separate planes as also illustrated in Figures 2 and 3. The end flange portions 45 on one side of the off-sets 49 are at a lower level than the end flange portions on the other side of the off-sets 49. As a result the longitudinal flange portion 44 is above the level of the longitudinal flange portion 43 on the opposite edge of the section. It will thus be noted that the longitudinal flange 44 is accordingly above the level of the flange portion 24 to which it is hinged so that the hinge 14 is vertically off-set.

When the carton is closed it will be noted that the section 11 is pivoted onto the section 10 and the section 13 is pivoted over the section 11. The off-sets 47 and 49 are so arranged as to coincide with one another. However, these off-sets 47 and 49 are on one side of the center line of the sections, while the off-set 46 is on the opposite side of the center lines thereof. As a result an opening 50 may be provided between the end flange portions 23 and 37. These openings 50 may serve as ventilation openings if it is so desired.

In Figure 4 of the drawings I disclose three cartons A arranged in side by side relationship. It will be noted that the superimposed flanges on one longitudinal side of each carton are above the level of the flange portions on the opposite sides of the cartons so that the flanges of adjacent cartons overlap. This arrangement is desirable for several reasons. In the first place the spacing between the longitudinal centers of adjacent cartons may be substantially decreased by the overlapping construction. Secondly it will be noted that each flange abuts against a side wall of the adjacent carton rather than against the flange edge thereof. If the flanges on both sides of the carton were on a common horizontal plane, the edges of the flanges would abut. By overlapping the flanges as disclosed in Figure 4 of the drawings each of the overlapping flanges abuts against the wall of the adjacent carton forming a double thickness spacer between these cartons. The cartons are accordingly more readily held in place.

In Figure 5 of the drawings I disclose cartons B in side by side relationship with the flanges of adjacent cartons arranged in overlapping relationship. The cartons B are similar to the cartons A previously described, with the exception of the fact that the off-set portions in the end flange portions of the various sections of each carton are arranged in registry. The composite flanges 51 on one side of each carton in folded condition are below the level of the composite flanges 52 on the opposite longitudinal side of each carton and the off-sets 53 connecting the flange portions 51 and 52 are centrally located between the longitudinal carton edges. As a result the flanges of the three sections are in

continuous contact throughout the periphery of the sections and the ventilating openings 50 are eliminated.

In Figure 6 of the drawings I disclose a series of cartons C which are also similar in general form to the cartons A and B previously described. However, the cartons C are provided with flanges which gradually incline from one longitudinal edge of each section to the other longitudinal edge thereof. As a result the flanges on one side of the carton are at a higher level than the flanges at the opposite side thereof so that the flanges of adjacent cartons may overlap.

It will be noted that the various sections of the carton C are so arranged that the composite flanges 54 along one longitudinal edge 55 of each carton are below the level of the composite flange structure on the opposite longitudinal edge 56 of each carton. In this structure as in the cartons B the flanges encircling all of the sections are in continuous contact throughout the entire periphery of the sections.

I have described my carton structure as useful on cartons having three foldably connected sections. While I prefer to employ a carton of this type, it is also possible to apply my construction to cartons having two sections hingedly connected together. For example the egg carton could comprise merely the sections 10 and 11 hingedly connected together with the cover section 13 omitted. Such a carton is not possessed of all of the advantages of the specific carton described but may be employed. Similarly the carton could be formed of two pivotally connected sections such as the sections 10 and 13 with the section 11 omitted. Such a carton does not provide the protection for the eggs of the three section carton described, but could be employed if desired.

The posts 17 and the projections 16 have been shown in the drawings as being generally octagonal in shape at the top and round in shape at the bottom. Obviously these posts could be octagonal in general both at the top and bottom or could be round both at their upper and lower extremities.

In accordance with the patent statutes, I have described the principles of construction and operation of my egg carton, and while I have endeavored to set forth the best embodiments thereof, I desire to have it understood that obvious changes may be made within the scope of the following claims without departing from the spirit of my invention.

I claim:

1. A carton for fragile articles including two elongated sections, said sections comprising tray shaped bodies having flanged encircling edges, the longitudinal edge of one section being connected hingedly to the longitudinal edge of the other section, the end portions of said flanged edges being off-set intermediate said longitudinal edges so that the flanged longitudinal edge on one side of each section is above the level of the flanged longitudinal edge on the other side of each section.

2. A carton for fragile articles including two elongated sections, said sections comprising tray shaped bodies having flanged encircling edges, the longitudinal edge of one section being connected hingedly to the longitudinal edge of the other section, the end portions of said flanged edges being off-set intermediate said longitudinal edge so that the flanged longitudinal edge on one side of each section is above the level of the flanged longitudinal edge on the other side of each section, the off-set portions of the two sections being spaced when said sections are folded into superimposed relation to provide an air space between said flanged edges at each end of said sections.

3. A carton for fragile articles including two elongated sections, said sections comprising tray shaped bodies having flanged encircling edges, the longitudinal edge of one section being connected hingedly to the longitudinal edge of the other section, the end portions of said flanged edges being off-set intermediate said longitudinal edges so that the flanged longitudinal edge on one side of each section is above the level of the flanged longitudinal edge on the other side of each section, said off-set portions being in contacting relation when said sections are folded into superimposed relation.

4. A carton in accordance with claim 1, in which there is an additional cover section hingedly connected to the second longitudinal edge of said other section, which cover section has end portions between longitudinal edges thereof provided with offset edges adapted to nest with the offsets of a section therebeneath when the carton is closed.

5. A carton in accordance with claim 4, in which the offsets of the end portions of the flanged edges of the respective tray-shaped body sections are spaced laterally from one another in the horizontal direction of those portions, whereby to define end openings therebetween.

6. A carton in accordance with claim 1, in which the offsets of the end portions of the flanged edges of the respective tray-shaped body sections are spaced laterally from one another in the horizontal direction of those portions, whereby to define end openings therebetween.

PAUL K. SCHILLING.
